UNITED STATES PATENT OFFICE

172,136

VACUUM CLEANER

Gordon W. Florian, Bridgeport, Conn., assignor to
Air-Way Electric Appliance Corporation, To-
ledo, Ohio, a corporation of Delaware

Application October 20, 1953, Serial No. 27,238

Term of patent 14 years

(Cl. D9—2)

To all whom it may concern:

Be it known that I, Gordon W. Florian, a citizen of the United States and a resident of Bridgeport, Connecticut, have invented a new, original, and ornamental Design for a Vacuum Cleaner, of which the following is a specification, reference being had to the accompanying drawing, forming a part thereof.

In the drawing:

Figure 1 is a side elevation of a vacuum cleaner, showing my new design;

Figure 2 is a side elevation showing another side of the vacuum cleaner;

Figure 3 is a front end elevation of the vacuum cleaner; and

Figure 4 is a rear end elevation of the vacuum cleaner.

I claim:

The ornamental design for a vacuum cleaner, as shown.
